(57) **CLAIM**

The ornamental design for a ceiling tile edge support clip, as shown and described.

DESCRIPTION

FIG. 1 is a front top perspective view of a ceiling tile edge support clip showing my original design;

FIG. 2 is a rear bottom perspective view of the ceiling tile edge support clip of FIG. 1;

FIG. 3 is a right side elevation view of the ceiling tile edge support clip of FIG. 1;

FIG. 4 is a rear bottom perspective view of a further embodiment of the ceiling tile edge support clip of my original design having a flush tab extending rearwardly therefrom;

FIG. 5 is a front top perspective view of the ceiling tile edge support clip of FIG. 4; and,

FIG. 6 is a left side elevation view of the ceiling tile edge support clip of FIG. 4.
